UNITED STATES PATENT OFFICE.

JOHN A. HOLMQUIST, OF WOODLAWN, PENNSYLVANIA.

MACHINE FOR MAKING WIRE REELS.

Application filed December 30, 1922. Serial No. 808,842.

To all whom it may concern:

Be it known that I, JOHN A. HOLMQUIST, residing at Woodlawn, in the county of Beaver and State of Pennsylvania, a citizen of the United States, have invented or discovered certain new and useful Improvements in Machines for Making Wire Reels, of which improvements the following is a specification.

10 In Letters Patent of the United States No. 1,375,844, granted me April 26, 1921, I have described and claimed a reel for wire, formed itself of wire. I shall in this application describe and claim machinery by 15 which the reel of the said Letters Patent may be produced in such quantity production as conditions of wire production require.

In the accompanying drawings Fig. I is a 20 view partly in plan and partly in horizontal section of the machine unit in which the wire used in forming the reel is shaped preliminarily into loops and cut into looped units; Fig. II is a view in end elevation of 25 this same machine unit. Fig. III is a view in elevation of the initially formed loop or reel unit; Figs. IV and V show the reel units after shaping; and Fig. VI shows in perspective the completed reel.

30 Referring, first, to Figs. I and II of the drawings, the machine unit there shown consists essentially of a rotatable block 1, a tension device 2, and a shear 3.

The block 1 is of columnar form, so particularly shaped that it imposes on the wire wrapped under tension upon it, the desired looped or elongate hoop form; that is to say this columnar block in cross section is of the shape and size to which the wire is to be initially shaped. The block is tapered slightly from its base, where the wire is wrapped on to the outer end whence the loops are delivered. It is mounted for rotation on its columnar axis.

45 As particularly shown in the drawings, the block may be built up, of a central body, to which the numeral 1 is immediately applied, and opposite removable and replaceable terminal members 4. This construction 50 makes possible the alternate application of terminal members of different size, and production of reel units of different size.

The tension device may be such as is found suitable. The wire which ordinarily 55 I use to form these reels is three sixteenths of an inch in diameter, and a suitable ten-

sion device is found in a pair of rolls 7 mounted in housings, as indicated at 2 and forming between them a roll pass, and in guide rollers 5 and 6. The arrangement is clearly shown in Fig. II, where the advancing wire is shown at W and the direction of advance is indicated by an arrow.

The shear is carried by the columnar shaping block 1, 4, and at its outer end. It 60 consists of a blade 8 embedded in the block and a relatively movable blade, to which the numeral 3 is immediately applied borne by a beam 9 which is pivoted upon the outer end of the block. This beam is, by means 65 of the cam drive shown, and including cam-wheel 10, lever 11, and push-rod 12, caused to swing and to effect one cut of the shears with each complete rotation of the block.

70 Operation will readily be understood. A fed-in length of wire is temporarily secured to the columnar block and the block is put in rotation. The wire is laid under tension around the block at its base or inner end. Being laid on under tension, permanent 75 shape is imposed upon it. The successive turns of wire, accumulating, force the already wrapped turns from the base outward, until the whole face of the block is covered with successive turns. Then with each revolution the shears cut free one loop and the freed loop is automatically delivered from the outer end of the block. It will be perceived that by virtue of the arrangement 80 shown and described, and particularly by 85 virtue of the fact that the beam 9 is pivoted upon the block 1, and that the push-rod 12 extends axially through block 1, the loops as they are formed pass freely from the end 90 of the block.

95 These loops are taken one by one as they are delivered from the machine of Figs. I and II and the cut ends are by familiar means not necessary here to describe, welded together to form the elongate hoops or blanks 100 A, such as illustrated in Fig. III.

It is not necessary that these blanks be all 105 of a size. As has already been intimated, and as presently will more fully appear, in the make-up of the reel the blanks are shaped to two particular reel units (Figs. IV and V), and the blanks for these several units may be of different size, and still a symmetrical reel will be produced. And for 110 particular conditions of service such variation in size, resulting in relatively long and relatively short reels, may be found desir-

able. For ordinary service in a steel wire mill, and particularly for the packaging of barbed wire for the market, I find a reel made from loops which are all of a size, to 5 be entirely satisfactory.

And it is manifest that the cross-sectional shape of the columnar block 1, shown in this particular instance to be elliptical, may be of any particular shape desired, adapting 10 the blank to its further use. It might manifestly be circular in cross-section, or square, or diamond-shaped,—what one will. But the elongate shape shown affords blanks suitable in shape for the production of the 15 particular article here in contemplation.

Associated with the machine illustrated in Figs. I and II, will be machinery for bending the loops which are formed and cut in the machine of Figs. I and II (after their 20 ends have been united) to the particular shapes shown in Figs. IV and V. And additional machinery will ordinarily be provided for securing the assembled parts, as shown in Fig. VI. It will be perceived that 25 the completed reel of Fig. VI is made up of four parts: two such as that illustrated in Fig. IV, two such as that illustrated in Fig. V. The ultimate step in making the reel, performed by the machine last alluded to, 30 shapes the corners *c* of the reel part shown in Fig. V to the eyes similarly designated in Fig. VI.

In a co-pending application filed by me I describe and claim machinery for fabricating the loops which are the product of 35 the machine of this application.

I do not here dwell upon the particular features of the reel which give it utility; these are sufficiently considered in my patent 40 mentioned above.

I claim as my invention:

1. In a wire-loop forming machine the combination of a columnar forming-block borne upon the end of a rotary shaft and provided with an interior longitudinal perforation, a beam pivotally mounted upon the free end of said forming-block and arranged within the path of advance of loops delivered from the free end of the forming block, a beam-swinging rod extending through and movable longitudinally within the perforation in the forming block and protruding beyond the free end of the forming block and there engaging the said beam, and a pair of shear blades borne, one by 45 said block, the other by said beam.

2. In a machine for forming reels out of wire, a machine unit consisting of a rotary columnar forming block compounded of a central body and opposite terminal members 50 carried by and removable from and replaceable upon said central body, and a shear carried by said block and opening and closing in synchronism with block rotation.

3. The combination of drum 1, provided with an axial bore, beam 9 pivoted upon the end of the drum, rod 12 reciprocable within the bore with which the drum is provided, protruding from the head of the drum and there engaging said beam, shear 55 blade 3 borne by said beam, and means for effecting co-ordinated rotation of the drum upon its axis and oscillation of said rod.

In testimony whereof I have hereunto set my hand.

JOHN A. HOLMQUIST.
